(57) CLAIM

The ornamental design for a mirror, as shown and described.

DESCRIPTION

A portion of the disclosure of this patent document contains material which is subject to copyright protection. The copyright owner has no objection to the facsimile reproduction by anyone of the patent document or the patent disclosure, as it appears in the Patent and Trademark Office patent files or records, but otherwise reserves all copyright rights whatsoever.

FIG. 1 is a front view of the new design;

FIG. 2 is a side view thereof; the other side view is identical and therefore not shown; and,

FIG. 3 is a top view thereof; the bottom view is identical to the top view and therefore not shown.

The back is not part of the ornamental design and is therefore not shown.
